[57] CLAIM

The ornamental design for a housing for an electrical connector, as shown and described.

DESCRIPTION

FIG. 1 is a front, top and right side perspective view of a housing for an electrical connector showing out new design;

FIG. 2 is a rear elevational view thereof;

FIG. 3 is a front elevational view thereof;

FIG. 4 is a left side elevational view thereof;

FIG. 5 is a top plan view thereof;

FIG. 6 is a bottom plan view thereof; and

FIG. 7 is a front, top and side perspective view thereof, positioned for coupling to a mating housing, the mating housing and conductors shown in broken lines are for illustrative purposes only and form no part of the claimed design.

*FIG. 1**FIG. 2**FIG. 3**FIG. 4**FIG. 5**FIG. 6*
